CLAIM

The ornamental design for strap end retainer with open slots.

DESCRIPTION

FIG. 1 is a front-right side perspective view of a strap end retainer with open slots showing my new design;

FIG. 2 is a front-right side perspective view thereof showing the retainer deployed around a strap end with no claim to the portions shown in dashed lines;

FIG. 3 is a front side elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a rear side elevational view thereof.
